FORM TURNING TOOL MECHANISM

Leslie W. Haynes, Windsor, Vt., assignor to Cone
Automatic Machine Company Inc., Windsor,
Vt., a corporation of Vermont

Application October 27, 1944, Serial No. 560,677

3 Claims. (Cl. 82—17)

1

This invention relates to a tool mechanism adapted to be carried by a tool carriage restricted to in and out motion but by the use of which a turning tool carried thereby may be made to traverse the work in addition to the in and out motion of the tool slide.

A further object of the invention is to provide such a mechanism wherein, if desired, the turning tool may cut tapers to an adjustable degree.

Still another object is to provide such a mechanism adapted to be carried by any of the front and rear tool carriages of a multiple spindle lathe, the traversing action being effected as by cams on an actuating shaft.

For a complete understanding of this invention, reference may be had to the accompanying drawings in which

Figure 1 is a fragmentary rear elevation of a multiple spindle lathe of the well known Cone type showing the mechanism of the invention applied to the top back tool carriage.

Figure 2 is a sectional view on line 2—2 of Figure 1.

Figure 3 is a somewhat diagrammatic fragmentary top plan view of the mechanism and a work piece showing the tool having made an initial cut and before the start of traverse.

Figures 4 and 5 are views similar to Figure 3, but showing the tool at the completion of a straight traverse and in retracted position after such traverse, respectively.

Figure 6 is a view similar to Figure 4, but showing the mechanism set for taper turning.

Figure 7 is a view of the mechanism partly in top plan and partly broken away and in section and to a much larger scale than Figures 3 to 6, inclusive.

Figure 8 is an end elevation of the mechanism similar to a portion of Figure 2, but to the scale of Figure 7.

Figure 9 is a detail sectional view to a larger scale on line 9—9 of Figure 1.

Referring first to Figures 1 and 2, there is illustrated a multiple spindle lathe of the well known Cone type having a work spindle carrier 1 indexable about a central axis 2 and carrying rotary work spindles in parallelism with the axis 2 and arranged therearound in circular series as at 3. In the machine shown, four such spindles are employed, but the number is not material to this invention. At the front and back of the machine, are mounted two slides, the upper slides being indicated at 5 and 6 in Figures 1 and 2, and there may be lower similar slides, these slides being movable from and toward work carried by the

2

spindles, two of these slides being mounted to move backwardly from the forward face of the machine, and the other two being mounted to move forwardly from the back face of the machine to cause a tool carried thereby to operate on work. There may be lower slides 7 and 8 similarly mounted and movable toward and from the two lower work spindles in each indexed position of the spindle carrier. The subject matter of this invention may be applied to any of these tool carriages, but as shown it is applied to the upper back tool carriage so that the tool carried thereby may operate on work held by the top rear spindle in each indexed position of the carrier.

15 Machines of this type are provided with overhead actuating cam shafts, such a shaft being shown at 10, and to this shaft are fixed cam drums, certain of which are illustrated in Figure 1. This machine is substantially as shown in the Cone Patent No. 2,142,557, granted January 3, 1939. The front and back tool carriages or slides are arranged to be moved in toward the work pieces carried by the spindles or retracted therefrom by suitable cams carried by cam drums on the shaft 10, and as shown this is accomplished by the use of vertically arranged rock members such as 14, each rock member having an arm 15 to which a bar 16 may be secured, these bars being moved by suitable cams on certain of the 20 cam drums as is disclosed in the Cone patent to which reference has been made. The rock members 14 have other arms 17 which are connected through links 18 and eyebolts 19 to the various tool carriages. Each of the tool carriages has a 25 slotted portion 20 for the reception of a tool or tool holding member.

In accordance with the present invention a block 22 may be inserted in the portion 20 of one of the slides such as the slide 6, and be fixed 30 in position as by a strap 25 extending thereacross and secured to the slide 6 as by bolts 27. The block 22, as best shown in Figures 3 to 7, has pivoted thereto, as on the pivot pin 30, a slideway member 31, and in order to adjust the angular 35 relation between this member 31 and block 22, this block 22 may have journaled therein a bolt 32 having its threaded extremity passing through a slot 33 in the slideway member 31 and threaded into a pin 34 journaled in the block 31. The 40 bolt 32 being threaded into the pivot 34 causes a transverse movement of this pivot 34 by the turning of the bolt, this, in turn, imparting a motion to the member 31 about its pivot 30. As 45 shown best in Figure 7, the hole in the block 22 50 where the bolt 32 passes, is enlarged for the 55

greater portion of its length from the bore necessary to pass the bolt so that the bolt may be free to flex as it is turned to provide for lateral displacement of the pivot 34, due to the fact that it moves about an arc described about the axis of the pivot 33 as a center. As the amount of adjustment of this bolt is not large, this enlarged portion provides for sufficient flexure of the bolt to follow the pivot 34 in its arcuate path. By adjustment of this bolt 32, the forward face of the member 31 may be adjusted angularly into or out of parallelism with the axis of the adjacent work spindle.

In Figures 3 and 4 the adjustment is such that the guideway of the member 31 is arranged parallel to the work axis. Member 31 is provided with a guideway 40 in its forward face (see particularly Figure 8) within which is slidably guided a tool slide 41 retained by guide strips 400 and 401 to which slide, by any suitable means, a turning tool 42 may be secured. It will be evident that as the slide 41 is moved in its slideway, the tool carried thereby is caused to traverse the work, and if the base of the guideway is exactly parallel to the work axis, this motion of the slide will cause the tool to traverse the work and form a straight or non-tapering cut thereon. If, however, the slideway is adjusted angularly, as shown, for example, in Figure 6, so that the path of motion of the slide 41 is not parallel to the work axis, such sliding motion of the tool slide will produce a tapered cut in the work as illustrated in Figure 6. Axial motion of the tool slide 41 may be produced by mechanism actuated by one or more cams on the cam shaft 10. Thus as shown in Figure 1, the tool slide is connected through a ball and socket or universal joint 45, shown in detail in Figure 9, to one arm 46 of a lever fulcrumed at 47 on the machine frame. This joint 45, as shown, comprises a socket means 450 threaded onto a plug 451 carried by one connecting member 452 and housing a ball end 453 of a second connecting member 454. The other end of the lever 46 carries a cam follower roll 48 adapted to be swung by certain cams (not shown) secured to one of the cam drums. Thus as the cam shaft rotates, the cams cause rocking of the lever 46, the corresponding pushing and pulling exerted through the joint 45 causing the tool slide to be traversed along its slideway. The parts are so timed that the tool carriage first moves inwardly to present the tool to the work, and produce a cut of the desired depth as shown at 50 in Figure 3. While the tool carriage remains in this inward position, the lever 46 is then actuated to move the tool slide 40 along the slideway, thus extending the cut 50 as shown in Figure 4, or in case of a tapered cut as shown in Figure 6. The tool slide may then be retracted as shown in Figure 5, bringing the tool out from the work, whereupon the slide may be returned to its initial position shown in dotted lines in Figure 5 ready for the succeeding operations on the next piece of work which is presented in proper relation to the tool by the indexing motion of the spindle carrying turret.

Thus it will be seen that while the tool carriage is provided with an in and out motion only with respect to the work carried by the work spindle in proper indexed position, the motion of the tool slide gives an additional component of motion lengthwise of the work piece which may be either straight or taper, depending upon the angular adjustment of the member 31.

From the foregoing description of an embodi-

ment of this invention, it should be evident to those skilled in the art that various changes and modifications might be made without departing from the spirit or scope of this invention.

5 I claim:

1. The combination with a lathe having a rotary work spindle, a tool carriage movable laterally toward and from work carried by said spindle and means for so moving said carriage, of a block fixed to said carriage, a slideway member pivoted to said block, said member having a slideway adjustable by the angular adjustment of said member about its pivot in a plane containing the axis of said spindle into or out of parallelism with said axis, means for producing such angular adjustment of said member, a slide movable in said slideway, a tool carried by said slide, an actuating shaft, and driving means actuated by said shaft for moving said carriage and said slide in predetermined coordination to cause said tool to traverse the work in the direction determined by the motion of said slide and the angular adjustment of said member.
2. In combination with a lathe having a rotary work spindle, a tool carriage movable laterally toward and from work carried by said spindle, and means including a cam shaft having cams thereon for so moving said carriage, of a block fixed to said carriage, a slideway member pivoted to said block, said member having a slideway adjustable by the angular adjustment of said member about its pivot in a plane containing the axis of said spindle into or out of parallelism with said axis, means for producing such angular adjustment of said member, a slide movable in said slideway, a tool carried by said slide, and means actuated from cams on said cam shaft and co-ordinated with the motion of said tool carriage for moving said slide to cause said tool to traverse the work in the direction determined by the motion of said slide and the angular adjustment of said member.
3. In combination with a lathe having a rotary work spindle, a tool carriage movable laterally toward and from work carried by said spindle, and means including a cam shaft having cams thereon for so moving said carriage, of a block fixed to said carriage, a slideway member pivoted to said block, said member having a slideway adjustable by the angular adjustment of said member about its pivot in a plane containing the axis of said spindle into or out of parallelism with said axis, means for producing such angular adjustment of said member, a slide movable in said slideway, a tool carried by said slide, and means actuated from cams on said cam shaft and co-ordinated with the motion of said tool carriage for moving said slide to cause said tool to traverse the work in the direction determined by the motion of said slide and the angular adjustment of said member, said cam shaft actuated means including a universal joint.
